UNITED STATES PATENT OFFICE

124,418

DESIGN FOR A DRESS OR SIMILAR ARTICLE

Margaret Gaudiosi, New York, N. Y.

Application September 7, 1940, Serial No. 94,870

Term of patent 3½ years

To all whom it may concern:

Be it known that I, Margaret Gaudiosi, a citizen of the United States, residing at 27 West 96th Street, New York city, in the county of New York and State of New York, have invented a new, original, and ornamental Design for a Dress or Similar Article, of which the following is a specification, reference being had to the accompanying drawing, forming part thereof.

I claim:

The ornamental design for a dress or similar article, substantially as shown.

MARGARET GAUDIOSI.
